CLAIM

The ornamental design for a lighting fixture quadra-partite dome reflector, as shown and described.

DESCRIPTION

FIG. 1 is an isometric view of a lighting fixture quadra-partite dome reflector showing our new design;

FIG. 2 is a front elevational view thereof;

FIG. 3 is a top plan view thereof;

FIG. 4 is a side-elevational view thereof; and,

FIG. 5 is a bottom plan view thereof. The broken line showing of other parts of a lighting fixture are for illustrative purposes only and forms no part of the design.
